CENTERING DEVICE.

1,040,715.

Specification of Letters Patent.

Patented Oct. 8, 1912.

Application filed December 3, 1909. Serial No. 531,285.

To all whom it may concern:

Be it known that I, HARRY MANN, a citizen of the United States, and a resident of Brooklyn, in the county of Kings and State 5 of New York, have invented certain new and useful Improvements in Centering Devices, of which the following is a specification.

The present invention relates generally to 10 centering devices to be used for lathes, shapers, planers, etc., and has more particular reference to an electrical centering device of the character indicated.

The object of the invention is to produce 15 a highly sensitive centering device capable of detecting minute improper displacement of work, or irregularities of surfaces.

Accordingly, the invention comprises a centering device having an electrical switch 20 and switch controlling means adapted to be actuated by the work to be centered. A suitable signal, such as a lamp or other means is under the control of the switch. This switch will preferably have a movable 25 switch member which is adapted to be moved in one direction by the work to be centered, either to make or break contact, according to the particular form in which the invention may be embodied, and in connection with this there are means provided 30 for normally moving said movable switch member in the opposite direction. In the more particular form here followed, this movable member consists of a spring-pressed 35 electrode and a contact member projecting beyond the tool body and adapted to actuate the movable electrode. In order to prevent the tool from breaking, should an excessive 40 pressure be applied, a yielding connection is interposed in said contact member which is adapted to yield when the movable electrode has reached the limit of its inward movement. The contact member preferably 45 is in the form of a plunger composed of two parts between which a spring is interposed.

Other features of construction will appear as the specification proceeds.

In the accompanying drawings the invention is disclosed in a concrete and preferred 50 form, from which form, however, wide variations may be made without departing from the legitimate and intended scope of the invention.

In the said drawings: Figure 1 is a general 55 view showing a portion of a lathe,

with the centering device in position. Fig. 2 is a longitudinal vertical sectional view of the centering device. Fig. 3 is a view showing an attachment which is used when it is desired to ascertain the displacement of the 60 inside bore or outside circumference of the work acted upon.

Similar characters of reference indicate corresponding parts in the different views.

In the said drawings, 1 indicates the face 65 plate of a lathe chuck carrying the work 2 to be acted upon.

3 indicates the tool post which may be of any approved form, dependent upon the particular lathe or machine to which the invention 70 is applied.

4 designates generally the centering device which may be inserted in the tool post and which may be held there by a screw 5, or other means. 75

The centering device itself consists of a body portion or casing 6, carrying a signal 7 which is here shown in the form of a lamp, and which is connected to the stationary electrode 8, in the present instance. The 80 movable member is composed of the movable electrode 10, normally held out of contact with the lamp terminal by means of the spring 11 pressing against the fixed or abutment member 30, and the plunger consists of 85 two members, one of which 12, is a contact member, and the other of which 13, imparts the motion of the contact head to the movable electrode. Interposed between the members 12 and 13 is a spring 14, of greater 90 resistance than the spring 11, so that when the contact member is depressed, said spring 11 will first yield, bringing the movable electrode into contact with the lamp terminal, while any additional inward movement will 95 then be taken up by the spring 14. Suitable electrical connections are made to a source of electrical supply 15, consisting in the present instance of the wires 16 and terminals 17 and 18. The terminal 18 is in contact with the stationary electrode 8, while the terminal 17 is in circuit with the movable electrode 10. These two electrodes are of course suitably insulated with relation to each other, in a well-known manner. 100

In practice, the centering device is inserted in the tool holder and the latter is then brought up against the face of the work to be centered until the movable electrode is brought into contact with the lamp terminal 110

and the lamp is lighted. If the work is now rotated and there should be any irregularity in the surface or in the parallel positioning of the work with reference to the chuck, the lamp will flicker, while, on the other hand, if the surface is perfectly true and the work is parallel to the chuck, the lamp will shine steadily.

When it is desired to ascertain whether or not the work has been placed properly with reference to the center of the face plate, chuck or other work carrying member, there is mounted a collar 19 on the end of the body portion or casing adjacent to the outer end of the contact member 12. This collar may be secured in position by means of the screw 20. Mounted upon this collar is a small bell crank 21 pivoted at 22 in the ears 23, one end of said bell crank bearing against the outer end of the contact member. If the centering device is now brought up against the work until the bell crank engages the inner bore or outside circumference of the work, sufficient to cause the lamp to be lighted, then the rotation of such work, if not properly centered, will cause the said lamp to flicker, while if the work is perfectly true, the light will remain steady.

The expression "centering device" has been used throughout this specification and throughout the claims to characterize the invention. This is not intended, however, as an expression of limitation, since, as shown, the function of the device is not always that of centering the work or detecting a displacement of the work away from the center, but also to detect the irregularities of surfaces.

In order to prevent short circuiting of the current, the movable contact member is preferably insulated from the body of the tool. This may be accomplished by surrounding said member with an insulating bushing 24, the current being led to the movable member by means of a projection 25 on the terminal 17, which engages the sleeve member 30 surrounding the member 10. The member 13 of the plunger is also provided on its inner end with a point 26 of insulating material for contact with the head of the movable electrode.

The insulated wires conducting the current to the electrode terminals are preferably placed in a longitudinal bore on the under side of the tool body and which terminates at the electrode terminals—so that the connections are easily made and the wires are fully protected and do not interfere in any way with placing the tool body on the post or in proceeding with the work. This feature is clearly disclosed in Fig. 2.

What is claimed, is:

1. A centering device comprising a tool body having a longitudinal bore, a plunger 65 slidingly engaged in the said bore, a signal

lamp mounted at the inner end of said bore, the tool body having an opening in the top thereof to expose said signal lamp, and a switch interposed between the inner end of the plunger and the lamp, adapted to be actuated by the said plunger. 70

2. A centering device comprising a tool body having a longitudinal bore therein, a plunger slidably engaged in the said bore, a signal lamp mounted in the tool body at 75 the inner end of the bore, the tool body having an opening to expose said signal lamp, and a switch interposed between the plunger and signal lamp, the said switch having a movable electrode adapted to be engaged 80 by the inner end of the plunger.

3. A centering device comprising a tool body having a longitudinal bore therein, a plunger slidably engaged in the said bore and consisting of a contact member having 85 an outer exposed portion for engagement with the work, an inner part, and a spring interposed between the two parts of the plunger, a signal lamp mounted in the tool body at the inner end of the bore, the tool body having an opening to expose said signal lamp, and a switch interposed between the plunger and signal lamp, the said switch having a movable electrode adapted to be engaged 90 by the inner part of the plunger. 95

4. A centering device comprising a tool body having a longitudinal bore, a plunger slidably engaged in the said bore, an electric signal mounted at the inner end of the bore, the tool body having an opening in the top thereof to expose the said signal, a switch interposed between the inner end of the plunger and the signal having a movable part to be engaged and actuated by the plunger, and means for conducting electric 105 current to the said switch.

5. A centering device comprising a tool body having a longitudinal bore, a plunger slidably engaged in the said bore, an electric signal mounted in the tool body at the inner end of the bore aforesaid, an electric terminal on the under side of the tool body having connection with the signal, a movable electrode interposed at the inner end of the bore in the tool body between the plunger and the signal, a second terminal on the under side of the tool body having connection with the movable electrode, the tool body having a passage extending longitudinally through the lower part thereof in line with 110 the terminals aforesaid, and electric conductors extending through said passage to the terminals. 115

6. In a centering device, a tool body, a signal carried by said tool body and having a stationary electrode, a stationary abutment member in said tool body, a movable electrode slidably mounted in said abutment member, means for holding said movable electrode out of contact with the stationary 125 130

electrode, insulation material insulating the abutment member and movable electrode from the tool body, a plunger slidably mounted in the tool body and adapted to move the movable electrode into contact with the stationary electrode, insulation between the plunger and the movable electrode, means for conducting current to the stationary electrode, and means, insulated from

the tool body, for conducting current to the abutment member.

Signed at Brooklyn, in the county of Kings and State of New York this 1st day of December A. D. 1909.
